UNITED STATES PATENT OFFICE.

GEORGE P. BUMP, OF LA CROSSE, WISCONSIN.

PENCIL HOLDER.

Application filed May 22, 1923. Serial No. 640,749.

To all whom it may concern:

Be it known that I, GEORGE P. BUMP, a citizen of the United States, residing at La Crosse, in the county of La Crosse and State 5 of Wisconsin, have invented certain new and useful Improvements in Pencil Holders, of which the following is a specification.

My invention relates to pencil holders and the object of the invention is to provide such 10 a holder for carrying in a coat pocket and to protect the pencil point.

The pencil holder consists of a stout metallic tube with a catch or clamp for securing it in the pocket and is provided with a 15 stop at its lower end, in order to prevent the pencil point from protruding through the holder, and it is furthermore provided with a spring so that the pencil will not accidentally fall out of the holder. Ordinary pencil 20 holders, now on the market, are made of very thin material and are apt to become crushed if excessive pressure is applied accidentally against the same. To overcome this difficulty, I construct my pencil holder 25 of heavy tubing, the walls of which could not possibly be upset by any pressure against the holder.

For this reason the pencil holder may, without danger, be carried with its clasp 30 attached to a belt or waist band, or even in a hip pocket.

In the accompanying drawing, one embodiment of the invention is illustrated; and—

35 Figure 1 shows a longitudinal section of the holder;

Figure 2 is a similar view to Figure 1 with the pencil inserted in the holder;

Figure 3 is a fragmentary longitudinal 40 section of the lower end of the holder; and

Figure 4 is a transverse section along line 4—4 of Figure 3.

The body portion of the pencil holder consists of a tubular member 10 of a length 45 sufficient to contain a pencil of ordinary length even permitting the same to protrude beyond the upper edge of the holder. This tubular member may be made from any suitable material having fairly thick walls, 50 such as brass or steel tubing. The upper edge of the tubular member 10 is upset to form an exterior flange 11, and the lower edge may likewise be upset by spinning, for instance, in order to form an inwardly 55 turned ledge 12.

Along one side of the tubular member 10

is placed a flat spring 13, which is hooked as at 14 at its lower end to rest on the ledge 12. This flat spring is straight as at 15 a short distance up from the hook 14, but from 60 there on is arched as at 16 to project across the bore of the tubular member 10 fully half its diameter. The extreme free end 17 of the spring is slightly upturned and lies against the same side of the bore as the 65 straight portion 15.

The spring is held in position by means of a short sleeve 18, also preferably made of suitable metal, and the outer diameter of which is slightly less than the inner diameter of the tubular member 10 so that the sleeve fits tightly therein. This sleeve has a double function, one is to retain the spring 70 in position at the bottom end of the tubular member 10 as best seen in Figure 3, and engages with its lower edge, the hook 14 holding the same tightly between itself and the ledge 12, while the straight portion 15 of the spring is pressed between the walls of the sleeve 18 and the tubular member 10. 75

The other function of the sleeve 18 is to form a shoulder as at 19 at its upper end, against which the tapering portion of the pencil 20 abuts when inserted in the pencil 80 holder, as best seen in Figure 2. The arcuate portions 16 of the spring tend to hold the pencil 20 tightly in the holder.

The clamp or clip for retaining the holder on the cloth consists of a downwardly directed bent arm 21 of resilient material having a bent lower end 22 normally contacting with the side of the tubular member 10. This clamp is provided with a pair of resilient fingers 23 which tightly grip around the tubular member 10 and abut against the 90 top flange 11 thereof. When attached to the clothing, the clamp engages with its arm 21 over the edge of the garment so that the holder will in this manner be prevented from slipping off. 100

The relative length of the sleeve 18 corresponds to the average length of a pointed pencil, so that the point thereof will not protrude beyond the ledge 12 and accordingly cannot be broken off. 105

Having thus described the invention, what is claimed as new is:

1. A pencil holder comprising a tubular member having an internal ledge at one end and an external flange at its other end, a 110 clamping member abutting against said flange, and means in said tubular member

adapted to firmly hold a pencil therein, said means engaging with said ledge.

2. A pencil holder comprising a tubular member having an internal ledge at one end and an external flange at its other end, a clamping member abutting against said flange, and means in said tubular member adapted to firmly hold a pencil therein, said means engaging with said ledge and including an arched spring contacting at both ends with the wall of said tubular member.

3. A pencil holder comprising a tubular member having an internal ledge at one end, means in said member adapted to firmly hold a pencil therein, said means engaging with said ledge and including an arched spring contacting at both ends with the wall of said member, and a sleeve inserted in said tubular member securing said spring therein.

4. A pencil holder comprising a tubular member having an internal ledge at one end,

means in said member adapted to firmly hold a pencil therein, said means engaging with said ledge and including an arched spring contacting at both ends with the wall of said member, and a sleeve inserted in said tubular member securing said spring therein, said sleeve providing a stop for the pencil.

5. A pencil holder comprising a tubular member having an internal ledge at one end and an external flange at its other end, a clamping member abutting against said flange, means in said tubular member adapted to firmly hold a pencil therein, said means engaging with said ledge and including an arched spring contacting at both ends with the wall of said tubular member, and a sleeve inserted in said tubular member securing said spring therein, said sleeve providing a stop for the pencil.

In testimony whereof I affix my signature.

GEORGE P. BUMP.
